LOADER FOR REVOLVERS

Hector Consuegra Lima, Habana, Cuba

Original application December 18, 1943, Serial No. 514,801. Divided and this application October 9, 1944, Serial No. 557,781. In Cuba April 5, 1943.

5 Claims. (Cl. 42—89)

1

This invention relates to loaders for revolvers of any well known type of mechanism.

This application is a division of the application Serial Number 514,801 filed December 18, 1943.

An object of this invention is to provide a loader adapted to transfer to the revolver the cartridges carried by it, by means of a simple rotatable control mechanism which in a predetermined position holds the cartridges within the loader and in another predetermined position releases the cartridges which may fall by gravity within the revolver chambers, whereby the loading operation of all the cartridges can be accomplished in a very short time not exceeding three seconds.

Another object of the invention is to provide the loader with an oil container forming part of the rotatable control mechanism and which is provided with a small air inlet and some oil outlet holes which in the cartridge release position of the control mechanism will permit the inlet of air and outlet of the oil, so that the oil may fall into the chambers of the revolver magazine and wet them thus serving as a cooling means to prevent excessive heating of the magazine as produced by repeated shooting.

The invention is described with reference to the figures of the accompanying drawing, of which:

Fig. 1 is a top plan view of the loader casing without the cartridge rotatable controlling member and without the cartridges.

Fig. 2 is an outer elevational view of the loader casing also empty.

Fig. 3 is a vertical section view on line 3—3 of Fig. 1.

Fig. 4 is a top plan view of the cartridge controlling member.

Fig. 5 is an outer elevational view of the cartridge controlling member.

Fig. 6 is a diametral vertical section view of the cartridge controlling member, on line 6—6 of Fig. 4.

Fig. 7 is a top plan view of the loader enclosing the cartridge controlling mechanism and the cartridges.

Fig. 8 is an outer elevational view of the loader fully charged.

Fig. 9 is a vertical section view of the loader on line 9—9 of Fig. 7.

Fig. 10 is a fragmentary enlarged horizontal section view of the central cylinder and three adjacent outer cylinders of the loader casing, showing the position of one of the projecting pins of the rotatable controlling member with relation to the notch in one of the outer cylinders and the relative position of the air openings in the position in which the cartridges are held by the projecting pins.

Fig. 11 is a detailed view similar to that of Fig. 10, showing the position of the same projecting

2

pins of the rotatable controlling member with relation to the notch in one of the outer cylinders and the relative position of the air openings in the position in which the cartridges are released.

5 In the drawing, Figures 1, 2 and 3 illustrate the casing of the loader forming the object of this invention. Said casing is metallic and is composed of a central hollow cylinder 1 opened at its upper end and closed at its lower end and six outer hollow cylinders 2 opened at their lower end and closed at their upper end, all being parallel to the central cylinder 1 and all surrounding the central cylinder 1 in its whole periphery to form a rigid unit by means of vertical joint lines which can be made by soldering. The outer cylinders 2 are all of the same length and diameter, their diameter being slightly greater than that of the flange cartridges 4 to be lodged within them and their length being somewhat smaller than that of the cartridges, so that once the latter are placed within the outer cylinders, they will project in about a third of their length outside the outer cylinders 2.

25 The cylinders 2 are symmetrically disposed about the central cylinder 1 in such a manner that a circle drawn by having its centre at the axis of the central cylinder 1, will intersect the axis of the six outer cylinders, the radius of said circle being equal to that of a similar circle drawn up at a revolver magazine to which the loader is 30 to be applied for the operation of transferring the cartridges from one to the other.

35 The cylinders 2 have an opening 3' at their top 3 to permit the examination of the percussion cap of each cartridge. Each cylinder 2 has near its top 3 a side notch 5 opposite the central cylinder 1, all notches 5 having their middle point at a like point located at the same side of a radial plane passing through the axis of the tangential line between the central cylinder 1 and the axis of the respective outer cylinder 2, for the purpose 40 hereinafter explained.

45 The central cylinder 1 has a length somewhat smaller than the length of each outer cylinder 2, so that its upper edge will just remain beneath the lower edge of each notch 5 and the flange 6 of each cartridge 4 when inserted in its respective cylinder 2 may remain above said lower edge of the notch 5 for the retention of the cartridge 50 as will be explained hereinafter.

55 Within the central cylinder 1 is lodged the manual cartridge control mechanism consisting of a metallic cylindrical receptacle 7 which is frictionally fitted within the central cylinder 1 so that it can rotate within said cylinder 1. Said receptacle 7 is greatly longer than the cylinder 1 by projecting upwards from the latter, the same being rotatably secured at its bottom to the bottom of cylinder 1, to which end the latter bottom 60 has a frusto-conical uprising portion 8

ending in an upper opening 9 adapted to give way therethrough to a screw 10 to be threaded from below to above so that its head will remain lodged within the depression formed by said uprising portion 8 and said screw will serve to fix the receptacle 7 by being screwed in a threaded socket 11 formed at the bottom of receptacle 7 which has a thickened portion of its peripheral wall forming an elongated neck 12 which is interiorly threaded and ends in a countersunk mouth 13 adapted to receive the head of a screw 14 threaded in said neck 12.

Said receptacle 7 serves as a container for a light oil adapted to serve as a cooling means when transferred to the magazine of a revolver to which the loader of this invention is to be applied. The container 7 has at its outer surface about a third of its height from its upper edge a series of six inter-spaced radial projecting pins 15 adapted to cooperate with the notches 5 of the outer cylinders 2 to retain or release the cartridges 4 according to the position adopted by the pins 15 respectively to said notches 5.

By rotating the cylindrical container 7 on the set screw 10, in one position the pins 15 will remain within the curved notches to hold the flanges 6 of cartridges 4 once these lodged in the respective cylinders 2 with their pointed portions downwards, and in another position, when the pins 15 are withdrawn from the notches 5 and reach the triangular hollow spaces 16 formed between the outer cylinders 2 and the central cylinder 1 (Fig. 7), the flanges 6 of the cartridges will be released and the cartridges will be allowed to fall out by their own weight along the respective cylinders 2. The control member 7 has near its upper edge three equidistant radial blades 17 projecting from the periphery of the member 7, their function being to serve as handles for rotating said member 7 the turn fraction necessary to place the pins 15 in position for retaining the flanges 4 or for releasing same.

To allow the egress of the oil occupying the inner space of the cylinder 1, through central cylinder 1, the container 7 has at its bottom a plurality of holes 18 arranged in a circular line and the central cylinder 1 is provided at its bottom with a plurality of holes 19 arranged in a circular line, as seen in Fig. 1, so that the oil from container 7 may fall over the bottom of central cylinder 1 through holes 18 and flow out through holes 19 at the bottom of the central cylinder 1, the oil thus discharged being adapted to be spread over the revolver magazine when the loader is applied to a revolver magazine for transferring thereto the cartridges 4 and to enter into the magazine chambers to serve as a cooling means each time a cartridge is shot. To allow the egress of oil from the container 7, the latter has beneath the plane of pins 15 and above the level of the contained oil 35 an air inlet hole 20 which in the position of the container 7 in which the cartridges 4 are released will register with another hole 21 formed in the wall portion of the central cylinder 1 adjacent the open space 16 so that outer air can enter into the container 7 above the level of the oil contained therein.

The operation of this loader is as follows: To load the loader the same is placed in an inverted position and the cartridges 4 are inserted within the receiving cylinders 2, one cartridge being inserted in each cylinder 2 with the percussion-cap carrying portion at the fore, until the flange 6 of each cartridge contacts the top

3 of each cylinder 2. Then, the container previously filled with oil 35 and obturated by screw 14 is inserted in the central cylinder 1 and its socket 11 screwed on the set screw 10 which is passed across the opening 9 of the frustro-conical bottom portion 8 of the central cylinder 1, the container 7 being let in the position in which its radial pins 15 abut the free end of the central cylinder 1 and penetrate in the notches 5 below the flanges 6 of the cartridges. The loader is transferred over the revolver magazine by centering its lower depression formed by the frustro-conical projection 8 on the small projection which the revolvers of whatever type or mechanism usually have at the upper portion of the magazine, whereupon, assuming the caliber of the revolver magazine is equal to the caliber of the loader 1-2, the cylinders 2 will remain in vertical alignment with the chambers of the revolver magazine and the points of cartridges 4 will be respectively introduced in the chambers of the revolver magazine. The control member 7 is then rotated on the set screw 10 until the radial pins 15 will be withdrawn from the respective notches 5 of the cylinders 2, whereupon the flanges 6 of the cartridges 4 will be freed from the pins 15 and the cartridges 4 will slide down by their own weight within the cylinders 2 and penetrate into the chambers of the revolver magazine, the revolver being thus loaded. The rotation movement of the control member 7 to release the cartridges 4 from the loader 1-2 will serve to cause the hole 20 of the control member 7 to register with the hole 21 of cylinder 1, so that as outer air enters into the rotatory container 7, the oil fallen into the cylinder 1 will flow out through holes 19.

It is obvious that changes may be made in the size, loading capacity and construction details of the loader, without thereby altering the essential character of the invention, which is such as claimed hereinafter.

What I claim is:

1. A loader for revolvers, comprising a central hollow cylinder open at its upper end and closed at its lower end, a plurality of cartridge receiving cylinders each closed at its upper end and open at its lower end and disposed adjacent one to the other all around said central cylinder and secured thereto to form a rigid unit, each cartridge receiving cylinder having near its top a lateral notch opposite the central cylinder, a manual cartridge control member rotatably mounted within said central cylinder and frictionally engaging the wall of the latter, and projecting means radially arranged on the cartridge control member and adapted to enter the notches of said outer cylinders, said radially projecting means in one position of said control member being adapted to engage the flanges of cartridges in the cartridge receiving cylinders, and in another position of said control member will be withdrawn from said notches and will be adapted to release the cartridge flanges.

2. A loader for revolvers, comprising a central hollow cylinder open at its upper end and closed at its lower end, a plurality of cartridge receiving cylinders each closed at its upper end and open at its lower end and disposed adjacent one to the other all around said central cylinder and secured thereto to form a rigid unit, each cartridge receiving cylinder being provided near its top with a lateral notch, the middle point of all notches being located at the same side of a radial plane passing through the axis of

the central cylinder and the axis of the respective cartridge receiving cylinder, a manual cartridge control member composed of a cylindrical container rotatably mounted within the central cylinder and frictionally engaging the wall of the latter, said manual cartridge control member being longer than said central cylinder to project beyond the open end of same, and a plurality of radial pins in a number equal to the number of the cartridge receiving cylinders and equidistantly arranged on the cartridge control member portion projecting from the central cylinder to so co-act with the notches of the cartridge receiving cylinders that in one position of the control member said pins will be positioned within the notches of the cartridge receiving cylinders and will be adapted to engage the flanges of cartridges placed in the latter, and in another position of said control member said pins will be withdrawn from said notches and will be adapted to release the cartridge flanges.

3. A loader for revolvers, comprising a central hollow cylinder open at its upper end and closed at its lower end, a plurality of cartridge receiving cylinders each closed at its upper end and open at its lower end and disposed adjacent to one another all around said central cylinder and secured thereto to form a rigid unit, the central cylinder having a length shorter than that of the cartridge receiving cylinders, each outer cylinder being provided near its top with a lateral notch, the middle point of all notches being located at the same side of a radial plane passing through the axis of the central cylinder and the axis of the respective cartridge receiving cylinder, a manual cartridge control member consisting of a cylindrical container rotatably mounted within said central cylinder and being of greater length than the latter to project beyond the open end of same, the bottom portion of said cartridge control member being provided with a central threaded socket, a screw passing through an opening in the bottom of the central cylinder and being screwed into the threaded socket of the cartridge control member permitting the latter to be rotated, and a plurality of radial pins in a number equal to the number of the cartridge receiving cylinders and equidistantly arranged on the control member portion extending beyond the central cylinder to so co-act with the notches in the cartridge receiving cylinders that in one position of said control member said pins will be positioned in the notches of the outer cylinders adapted to engage the flanges of cartridges placed in the cartridge receiving cylinders, and in another position of said control member said pins will be withdrawn from said notches and will be adapted to release the cartridge flanges.

4. A loader for revolvers, comprising a central hollow cylinder open at its upper end and closed at its lower end by a bottom wall, a plurality of cartridge receiving cylinders each closed at its upper end and open at its lower end and disposed adjacent to one another all around said central cylinder and secured thereto to form a rigid unit, a manual cartridge control member provided with a cylindrical container having a bottom wall and a side wall and adapted to receive a charge of a light oil, said control member being movably mounted within said central cylinder, and frictionally engages the inner wall of the same, means on said control member adapt-

ed in one position of the same to retain cartridges placed in said cartridge receiving cylinders, said means being adapted to release said cartridges from said cartridge receiving cylinders in another position of said control member, the central cylinder and the cylindrical container each having in their bottom wall a plurality of holes arranged along a circular line for discharging the oil contained in each, the central cylinder also being provided with a small hole in its side wall for outside communication and the control member being provided with a small hole in the side wall of its cylindrical container above the oil level therein, said side wall holes being adapted to register with one another in the position of the control member in which the cartridges placed in said cartridge receiving cylinders are adapted to be released from the latter, atmospheric air being thus allowed to enter the interior of the cylindrical container of the control member and a certain amount of oil allowed to be discharged from the central cylinder.

5. A loader for revolvers, comprising a central hollow cylinder open at its upper end and closed at its lower end by a bottom wall, a plurality of cartridge receiving cylinders each closed at its upper end and open at its lower end and disposed adjacent to one another all around said central cylinder and secured thereto to form a rigid unit, each cartridge receiving cylinder having near its top a lateral notch opposite said central cylinder, a manual cartridge control member provided with a cylindrical container having a bottom wall and a side wall and adapted to receive a charge of an oil, said control member being rotatably and frictionally mounted in said central cylinder and being of greater length than the latter to extend beyond the open end of the central cylinder, a plurality of radial pins equidistantly arranged on the portion of the cartridge control member projecting outside the central cylinder, said radial pins in a predetermined position of the cartridge control member entering the notches of the cartridge receiving cylinders and being adapted to engage the flanges of cartridges placed in the cartridge receiving cylinders and thereby serve as stops for the cartridges, said radial pins being adapted to be moved to another predetermined position by rotative adjustment of the control member in which said pins are withdrawn from the notches of the cartridge receiving cylinders and thereby being adapted to release the cartridges, the central cylinder and the cylindrical container each having in their bottom wall a plurality of holes arranged along a circular line for discharging the oil contained in each, the central cylinder being also provided with a small hole in its side wall for communication with the atmosphere and the control member being provided with a small hole in the side wall of its cylindrical container above the level of the oil contained therein, said side wall holes being adapted to register with one another in the position of the control member in which the radial pins thereof are withdrawn from the notches of the cartridge receiving cylinders, thereby permitting atmospheric air to enter the interior of the cylindrical container of the control member and causing a certain amount of oil to be discharged from the central cylinder.

HECTOR CONSUEGRA LIMA.
